(57) CLAIM

The ornamental design for a printer, as shown and described.

DESCRIPTION

FIG. 1 is a front perspective view of a printer showing our new design;
FIG. 2 is a front view thereof;
FIG. 3 is a rear view thereof;
FIG. 4 is a left side view thereof;
FIG. 5 is a right side view thereof;
FIG. 6 is a top view thereof;
FIG. 7 is a bottom view thereof;

FIG. 8 is another front perspective view thereof, showing the printer in an environment with an imaging device;
FIG. 9 is another front view thereof, showing the printer in alternate position; and,
FIG. 10 is another top view thereof, showing the printer in still another alternate position.
The broken lines illustrating portions of the printer depict environmental subject matter and form no part of the claimed design.
